UNITED STATES PATENT OFFICE.

PETER JOHN MARFELL, OF DUNEDIN, NEW ZEALAND.

APPARATUS FOR AUTOMATICALLY BALANCING CRANES.

1,195,058.

Specification of Letters Patent. Patented Aug. 15, 1916.

Application filed September 2, 1915. Serial No. 48,744.

To all whom it may concern:

Be it known that I, PETER JOHN MARFELL, architect's assistant, a subject of King George V of Great Britain, residing at 40 Dowling street, Dunedin, in the Dominion of New Zealand, have invented certain new and useful Improvements in Apparatus for Automatically Balancing Cranes, of which the following is a specification.

10 The object of this invention is to provide means whereby a crane or other machine used for raising, shifting and lowering weights of any kind, whose lifting boom or jib overhangs its support, may be automatically balanced according to the weight raised, shifted or lowered.

The method adopted according to this invention is to use the power required to divert from a straight line any part of the 20 hoisting rope or ropes, to which the weight is suspended, to transmit motion to a weighted car which may be termed a balance or counter weight and move it along a track, so that the said counter weight will balance 25 the loaded crane on its supports.

Referring to the drawings accompanying the specification:—Figure 1 is a side elevation showing the invention applied to an ordinary derrick crane. Fig. 2 is a plan view of Fig. 1. Fig. 3 is an end elevation of Fig. 1, a portion of the jib of the crane being removed. Fig. 4 is a side elevation showing the altered position of the counter weight and its operating parts when a load 30 is on the crane. Fig. 5 is a side elevation showing the altered position of the counter weight and the grade of the counter weight track due to the altered angle of the jib. Figs. 6 and 7 are, respectively, a side elevation and a plan view, on an enlarged scale, of the means shown in Figs. 1 and 2 for compensating for the varying angle between the hoisting boom and the support of the crane.

45 The invention is contemplated in connection with the ordinary derrick crane in which hoisting or load rope (1) which supports the load (2) is passed over a revoluble pulley (3) mounted near the rim of a revoluble grooved wheel (4) and under a pulley (5) mounted on a shaft (6), upon which said shaft (6) the grooved wheel (4) may also be mounted; the said shaft being supported by suitable bearings secured to the 50 jib (7) of the crane. It will be noticed that by so training the hoisting rope 1 over the

pulleys above mentioned the portion of the rope in passing over and under the pulleys (3) and (5) is diverted from a straight line and is then led to the winding drum on the 60 derrick of the crane. There is a traction rope (8) having an end fixed at a suitable point (9) on the rim of the grooved wheel (4), the said rope being adapted to lay in said groove of the wheel. The rope 8 is 65 led from the wheel 4 under a pulley (10) to a fairlead (10^A) mounted in a position near the base of the jib of the crane, and is then led over a pulley mounted on the outer end of the counter weight track (11) 70 and, finally, attached to the counter weight (12). The counter weight 12 is here shown as mounted on wheels or rollers and is adapted to travel back and forth along the track 11. The movement of the said counter 75 weight is controlled by the straightening of the load rope (1) when taking the strain of the weight to be lifted. The straightening of the rope partially rotates the grooved wheel (4) producing a movement in the 80 rope (8) in the direction of the arrow head (8^A) and thus transmits motion to the counter weight moving it rearward along the track (11) to a position where it will balance the weight which is suspended by the 85 load rope (1).

The compensation of the varying radius or angle of the hoisting boom or jib (7) relative to the support of the crane is arranged by altering the gradient of the counter balance track (11) pivotally attached to the derrick support (11^A) at (11^B) by means of a device actuated by the movement of the said jib. One method shown in Figs. 1, 2, 6 and 7 is the provision of gearing comprising a bevel wheel (13) mounted on the pivot shaft (14) of the jib (7) and adapted to mesh with a pinion (15) keyed to a shaft (16) suitably mounted on bearings, said shaft projects rearwardly in alignment with the counter weight track (11) and has on its rear end a bevel pinion (17) which is adapted to mesh with a bevel wheel (18) keyed to a shaft (19) mounted in suitable bearings bolted to the rear end of the counter weight 90 track support (20). There is a cam (21) keyed to the shaft (19) which engages with a friction roller (22) suitably mounted to the frame work of the said counter weight track (11) the said cam being actuated by 105 the adjustment of the jib through the medium of the said bevel gearing and rear- 110

wardly projecting shaft raises or lowers the said track altering the grade thereof, and effecting the distance through which the counter weight travels when the crane is 5 taking a load.

What I claim and desire to secure by Letters Patent is:—

1. A crane comprising, in combination, a frame, a hoisting boom pivoted to the frame, a counter weight movable on the frame, an actuating member for the counter weight mounted on said hoisting boom, and a hoisting line supported from the hoisting boom and having connection with said actuating member for moving said counter weight when a load is on said hoisting line.
2. A crane comprising, in combination, a frame, a hoisting boom pivoted to the frame, an adjustable support on the frame, a counter weight movable on said support, means for raising and lowering said boom, means for automatically varying the inclination of the support according to the position of said boom, an actuating member for the counter weight mounted on the hoisting boom, and a hoisting line supported on said hoisting boom and having connection with said actuating member for moving said counter weight when a load is on said hoisting line.
3. In a hoisting crane, and in combination, a hoisting line for the crane, a movable counter weight for balancing said crane when the hoisting line is subjected to a load, and an operating member for said counter weight and having connection with said hoisting line for interrupting the straight alinement of the latter when not under a load, said operating member being actuated 40 to operate said counter-balancing weight when the hoisting line is placed under a load.
4. The combination with a hoisting line of a hoisting crane, of a movable member supported on the crane and connected with the hoisting line, and a counter-balancing weight for the crane having a connection with said member and normally operating said member to retain a portion of the hoisting line diverted from a straight line, said member being actuated by said hoisting line to move said counter-balancing weight when a load is on said hoisting line.
5. In a derrick, a supporting frame, a hoisting boom on said frame, a wheel jour-

naled on said hoisting boom, a windlass on the derrick frame, a pulley mounted on and adjacent the periphery of said wheel, a pulley on the axis of said wheel, a counter-balancing weight mounted on the derrick frame 60 and adapted to be automatically adjusted thereon, connecting means secured to said weight and to the periphery of said wheel, and a hoisting line extending over the end of said hoisting boom and adapted to be wound 65 on said windlass, said hoisting line passing over the pulleys of said wheel at a point intermediate the end of said hoisting boom and said windlass.

6. In a derrick, a derrick frame, a hoisting boom pivoted to said frame, a counter-balancing weight for the derrick, a runway for said weight pivoted to said frame, a cam member mounted on the frame and having the cam surface thereof engaging with 75 said runway, and gearing between said hoisting boom and cam whereby the latter is rotated by the movement of the hoisting boom to vary the inclination of the runway.

7. In a derrick, a derrick frame, a hoisting boom pivoted to said frame, a counter-balancing weight for the derrick adapted to be automatically adjusted thereon, a runway for said weight pivoted to said frame, a cam member mounted on the frame and having 80 the cam surface thereof engaging with said runway, gearing between said hoisting boom and cam whereby the latter is rotated by the movement of the hoisting boom to vary the inclination of the runway, a wheel journaled on said hoisting boom, a windlass on the derrick frame, a pulley mounted adjacent the periphery of said wheel, a pulley on the axis of said wheel, connecting means secured to said counter-balancing weight 90 and to the periphery of said wheel, and a hoisting line extending over the end of said hoisting boom and adapted to be wound on said windlass, said hoisting line passing over the pulleys of said wheel at a point 100 intermediate the end of said hoisting boom and said windlass, substantially as described.

In testimony whereof I have hereunto set my hand in presence of two subscribing witnesses.

PETER JOHN MARFELL.
